(57) **CLAIM**

The ornamental design for a cover for earphone case, as shown and described.

DESCRIPTION

FIG. 1 is a front, top, and left-side perspective view of a cover for earphone case, showing my new design;

FIG. 2 is a front view thereof;

FIG. 3 is a back view thereof;

FIG. 4 is a left side view thereof;

FIG. 5 is a right side view thereof;

FIG. 6 is a top view thereof;

FIG. 7 is a bottom view thereof;

FIG. 8 is a back, top, and left-side perspective view thereof; and,

FIG. 9 is a front, bottom, and left-side perspective view thereof.

The broken lines shown in FIGS. 1-4 and 6-9 depict portions of the cover for earphone case, which form no part of the claimed design. The unshaded interior surfaces of the cover for earphone case, seen through openings in FIGS. 1, 2, 7, and 9, form no part of the claimed design.
